United States Patent Office.

EDWIN M. CHAFFEE, OF PROVIDENCE, RHODE ISLAND.

Letters Patent No. 78,260, dated May 26, 1868.

IMPROVED RUBBER AND GUTTA-PERCHA HOSE.

The Schedule referred to in these Letters Patent and making part of the same.

TO ALL WHOM IT MAY CONCERN:

Be it known that I, EDWIN M. CHAFFEE, of Providence, in the county of Providence, and State of Rhode Island, have invented new and useful Improvements in Rubber and Gutta-Percha Hose; and I do hereby declare that the following is a full, clear, and exact description thereof, which will enable those skilled in the art to make and use the same, reference being had to the accompanying drawings, forming part of this specification, in which—

The drawing represents a perspective view of a short section of my improved hose.

This invention relates to the formation of rubber or gutta-percha hose, whereby the same is, when not distended with water, made to occupy less bulk on the hose-reel or elsewhere.

Heretofore rubber or gutta-percha hose maintained its cylindrical or rotund form at all times, whether filled with water or not, and therefore was objectionably bulky, filling up the ordinary hose-reels with but a comparatively few lengths of hose.

It was also more difficult to handle.

These objectionable features I obviate by the process of manufacture now to be described, so that the above kinds of hose may remain collapsed, and, consequently, as easy to reel up and handle, when not distended, as the common leather hose, and also as susceptible of as close packing on the reel as the last-named kinds of hose.

The hose, which is, in general, made of any netting of textile material, cemented together in plies or layers, and having the exterior and interior surfaces of the hose proper, when completed, covered or coated with vulcanized rubber or gutta percha, is flattened by exterior plane surfaces, and placed within a heated chamber until the hose has acquired a permanent flat form, as shown in the drawing.

The hose is first made in the usual rotund form, and then placed between long plane surfaces, which are made to flatten the hose, and hold it so flattened, by means of weights, set-screws, clamps, or any suitable mechanical means.

This flattening of the hose is performed within long chambers, of sufficient longitudinal diameter to contain a single length of hose, and of sufficient lateral and vertical dimensions to contain a number of such lengths, side by side, and one above the other, a plane surface being interposed between each superimposed length.

As it is not desirable to permit the complete collapse of the hose, a long strip of metal, wood, or webbing, is inserted in each length of hose, which prevents the complete collapse of the hose, and thereby conduces to a more symmetrical appearance to the flattened hose.

The hose-chamber is then heated internally, by means of steam-pipes along its interior sides; or hot air or water may be injected at large, or forced within the chamber, for the same purpose; or, if more desirable, the flattening-planes before described (which should be of metal) may be the exterior surfaces of hollow plates, containing hot steam.

The hose may be treated as above described, before or after complete vulcanization; but I prefer to take the unvulcanized rotund hose, and submit it to the heat of vulcanization between the flattening-planes, as above described.

When hose, vulcanized or unvulcanized, is flattened by pressure, and submitted to heat, as above stated, it will, when cooled, retain its flattened form, which is superior to the rotund form, for the reasons mentioned.

The hose having been originally formed with a circular section, the plies or layers of textile material, composing the body of the hose, are in such correlation to each other as to take equally the strain of distension when water is forced through, for the flattening process does appreciably alter the original relation of the plies.

This treatment of hose is not expensive, and, if it is made to form part of the vulcanizing treatment, the expense of flattening the hose will be scarcely more than the first cost of the flattening-plates.

I claim as new, and desire to secure by Letters Patent—

The rubber or gutta-percha hose, flattened between plane surfaces, under the heat of vulcanization, substantially as described, for the purpose specified.

EDWIN M. CHAFFEE.
